UNITED STATES PATENT OFFICE.

HARRY F. FISHER, OF COLUMBUS, OHIO.

FUSE-BOX.

1,177,310.

Specification of Letters Patent. Patented Mar. 28, 1916.

Application filed January 11, 1915. Serial No. 1,510.

To all whom it may concern:

Be it known that I, HARRY F. FISHER, a citizen of the United States, residing at Columbus, in the county of Franklin and State of Ohio, have invented a certain new and useful Improvement in Fuse-Boxes, of which the following is a specification.

The object principally of this invention generally is to provide improved means whereby electric fuses, especially those for high tension currents, can be examined, handled and replaced with greater safety than heretofore.

The particular advantage of the improved means will more fully appear from the following description and claim.

In the accompanying drawing showing one embodiment of the invention—Figure 1 is a front view of the fuse box with the door 6 opened and disclosing the interior details. Fig. 2 is a longitudinal section of a portion of the box on the line α — α Fig. 1, showing in top plan view the upper end of the fuse. Fig. 3 is a similar horizontal section on the line y — y Fig. 1.

In the views 5 designates the box and 6 a door therefor hinged as at 7 to close the front of the box.

8 designates a stone base mounted and secured with suitable insulating devices 9 at the left hand end of the box. The base has upon it suitable binding posts 10, and 11 for connecting the electric line conductors. Mounted on the base in electric connection 35 with the binding posts are a standard 12 and the female member 13 of a knife switch.

14 designates the fuse. The fuse has at one end a knife 15 to engage the member 13, while the other end is held in a metal clamping frame 16 hinged at 17 to the standard 12. The clamping frame has one side flattened as at 18 to fit against a flat portion made on the fuse so that the knife 15 may be properly positioned to enter the member 12 when the fuse is swung upward on the hinge 17. A thumb screw 19, the proper turning of which serves to bind the clamp upon the fuse when inserted in the clamp or to permit the removal of the fuse when the

latter is to be examined or replaced with 50 another is provided. The hinging of the fuse supporting frame is such that the frame can be swung parallel to the front of the box and toward the end of the box opposite that near which it is hinged. Connected with 55 the clamping member by a hinging member 20 is a rod composed of an insulating portion 21 and a metallic portion 22, the two being united by a coupling 23 (preferably threaded). The aforesaid rod is of sufficient length to extend through a slot 24 which is made of just about the diameter of the rod where it passes through so that the coupling 23 shall also serve as a stop to abut against the end of the box and thereby 60 limit the throw of the rod and fuse as clearly illustrated by broken lines Fig. 1. The outer end of the rod is provided with a suitable knob for working it to oscillate the fuse. A hole 25 through the bottom of the box affords a passage for the flame of a fuse when being blown.

The practice with this invention is to pull down the fuse before opening the door of the box, and to close the door before shoving the fuse up into position. In this way "flashing" of flame in the face of the operator and the dangers and annoyances incident thereto are avoided. To replace a blown fuse the latter is first pulled down 75 and the door afterward opened after which the "blown" fuse can be safely removed and a new one put in its place. The door is then closed and the new fuse turned up into operative position.

Another advantage of this construction is that the obtaining of access to the interior of the box or to the fuse and appurtenances does not involve a serious exposure of the fuse and holders to rain or snow, all said 80 parts being amply protected by the roof of the box.

What I claim is:

A fuse box for high tension electric conductors having a closing door, contacts on 85 one side of the box, supporting means for a fuse hinged in electrical connection with one of said contacts to oscillate in a plane

parallel with the door when the latter is in closed position, and a pull rod connected with said fuse support and extending through an opening in the opposite side of 5 the box and operable from the exterior thereof while the door is closed for swinging said fuse support into or out of connection

with the other contact and thereby place the fuse into or out of circuit while the door is closed, substantially as shown and described. 10

HARRY F. FISHER.
